COMPUTING SIGHT

Edwin H. Ludeman, Brooklyn, N. Y.

Application August 5, 1947, Serial No. 766,429

27 Claims. (Cl. 33—49)

(Granted under the act of March 3, 1883, as
amended April 30, 1928; 370 O. G. 757)

1

The invention described herein may be manufactured and used by or for the Government for governmental purposes without the payment of any royalty thereon.

This invention relates to lead-computing gun sights. It is well known that, to effectively engage a moving target in combat, the gun must be aimed ahead of the target by an angle that is a factor of range, average velocity of the projectile, and speed of the target. In making such computations, the assumption is necessarily made that the target will continue in rectilinear movement at constant velocity during the time of flight of the projectile. Under such conditions, the angle of lead is the angle subtended at the gun by a distance equal to the product of velocity of target and time of flight of the projectile, such distance being laid off along the path of the target projected ahead of the position of the target at the time the gun is fired.

It is therefore an object of my invention to provide a lead-computing gun sight that is entirely self-contained and that, except for one manual adjustment, operates automatically to compute and apply the necessary lead-angle merely by the act of keeping a sight trained upon the target.

A further object is to provide a sight of the type described wherein reticle lines are projected into the field of view and are automatically moved and manipulated by the operation of the gun in tracking the target so that the gun has the proper lead when the target is properly positioned or "framed" between the reticle lines.

Another object is to provide a lead-computing sight of the type aforesaid, wherein the apparent spacing of reticle range lines is varied in accordance with a function of the angular velocity of the target and range.

A still further object is to provide a lead-computing gun sight wherein an image of the reticle lines is projected into the field of view including the target and the observable images varied along each of two mutually-normal coordinate axes in accordance with the angular velocity of the target from the gun position.

Another object is to vary the relation of the scale of reticle lines in the field of view of the telescope to correct for differences between the actual and measured angular rates of the gun.

A further object is to provide an angular rate-measuring mechanism wherein the settling time of the instrument, that is, the time required for the instrument to reach a steady state, varies in accordance with a function of the rate measured.

Yet another object is to provide an angular rate-measuring mechanism which is highly accurate and sensitive to small changes in angular rates and which, at the same time, may be ren-

dered insensitive to high rates, as when the gun is slewed to pick up a new target.

Still another object is to provide a lead-computing gun sight that is, except for an initial setting for range, automatic in operation, that is operable if desired, by one person, relatively simple in use, inexpensive to construct and capable of being used to a high degree of accuracy.

Another object is the provision of a method of determining the lead angle for a moving target by the mere act of moving a gun to maintain a line of sight directed thereon.

Other objects and advantages of my invention will become apparent as the description proceeds.

In the drawings:

Fig. 1 is a velocity diagram taken in a plane determined by the gun position and target path and showing the principle upon which my computer operates;

Fig. 2 is a vector diagram showing the factors determining the angle subtended at the gun by the assumed sphere of diameter equal to the wing span of an aerial target;

Fig. 3 is a perspective view of the left side of a gun equipped with my lead computer and showing the manually-operated elevation and azimuth controls and their extensions to the computer proper;

Fig. 4 is side elevation of the computer with cover plate removed;

Fig. 5 is a sectional view to an enlarged scale, taken upon a plane as indicated by line 5—5, Fig. 6;

Fig. 6 is a view corresponding to a portion of Fig. 4, but on an enlarged scale and showing in section the casing mounting the variable speed drive, sphere-driven castor and interconnected parts;

Fig. 7 is a view corresponding to a portion of Fig. 4 and showing to an enlarged scale the means for projecting the reticle into the field of view of the sight;

Fig. 8 is a section taken upon a plane indicated by the line 8—8, Fig. 7, showing the perforated reticle-forming disc pivoted into a typical position;

Fig. 9 is a detail view upon an enlarged scale, of the knob for adjusting the instrument to observed or apparent target size.

Figs. 10 and 10a show two typical views of a target as seen when correctly framed between reticle lines, for large and small ranges, respectively;

Figs. 11 and 12 show various suitable types of perforations in the reticle-forming disc;

Fig. 13 is a wiring diagram of a circuit to prevent the production of excessive lead angles dur-

ing slewing or rapid angular movement of the gun, as when picking up a new target;

Fig. 14 is an elevational detail view of a modified form of reticle-tilting mechanism;

Fig. 15 is a detail sectional view upon a plane indicated by the line 15—15, Fig. 6;

Fig. 16 is a schematic view of a cosine corrector suitable for use in introducing corrections for superelevation.

Referring to Fig. 1 wherein all points shown are supposed to lie in the slant plane determined by the gun and the target path, assumed to be a straight line, G indicates the position of a gun equipped with my computer, and which is to be fired at a target pursuing a course indicated by the line T_0 — T_p . T_0 indicates the present position of the target and T_p the predicted or future position at which a shell from gun G will strike the target. The distance T_0 — T_p is, then, equal to the linear speed S of the target, assumed to be constant, multiplied by the time of flight t_p of the projectile from G to T_p . The angle Δ is the angle subtended at the gun by the slant plane distance T_0 — T_p or St_p .

From the figure, it is clear that, approximately,

$$\sin \Delta = \frac{\Sigma D_o t_p}{D_p} \quad (1)$$

where Δ is the lead angle between the present and future gun-target lines, Σ is the angular velocity of the target in the slant plane as measured by the computer, t_p is the time of flight of the projectile, and D_p is the future or predicted range. Also, very closely,

$$D_p = vt_p \quad (2)$$

where v is the average velocity of the projectile to the point of impact T_p .

Substituting the value of D_p in (2) into (1),

$$\sin \Delta = \frac{\Sigma D_o t_p}{vt_p} = \frac{\Sigma D_o}{v} \quad (3)$$

or

$$\Delta = \arcsin \frac{\Sigma D_o}{v} \quad (4)$$

Also, since triangles T_0ab and GT_0C are similar,

$$\frac{T_0a}{T_0b} = \frac{GC}{GT_0} \quad (5)$$

In the velocity triangle T_0ab ,

$$T_0a = \Sigma D_o \text{ and } T_0b = S$$

In the space triangle GT_0C ,

$$GT_0 = D_o \text{ and } GC = D_M$$

Substituting these values in (5)

$$\frac{\Sigma D_o}{S} = \frac{D_M}{D_o} \quad \text{or} \quad D_o = \left[\frac{\Sigma D_o}{D_M} \right]^{\frac{1}{2}} \quad (6)$$

Substituting the value of D_o in (6) into (4)

$$\Delta = \arcsin \frac{[SD_M \Sigma]^{\frac{1}{2}}}{v} \quad (7)$$

Since Δ is always small, the difference between the angle and the sine thereof is negligible, whence,

$$\Delta = \frac{[SD_M \Sigma]^{\frac{1}{2}}}{v} \quad (8)$$

For a given engagement, S is assumed to be constant during the travel of the target from T_0 to C. Also for this run, T_0C , as well as for any other specific run, D_M and v are constant. Hence the value

$$\frac{[SD_M]^{\frac{1}{2}}}{v}$$

of Equation 8 is constant (k) and, for any two particular values of Δ such as Δ_2 and Δ_1 ,

$$\Delta_2 = k \Sigma_2^{\frac{1}{2}} \text{ and } \Delta_1 = k \Sigma_1^{\frac{1}{2}}$$

Hence

$$\frac{\Delta_2}{\Delta_1} = \left[\frac{\Sigma_2}{\Sigma_1} \right]^{\frac{1}{2}} \text{ and } \Delta_2 = \Delta_1 \left[\frac{\Sigma_2}{\Sigma_1} \right]^{\frac{1}{2}} \quad (9)$$

Referring to Fig. 2, let θ be the angle subtended at present range D_o by the wing spread W of a target craft. This wing spread is known as soon as the target is identified and, by assuming that the target is a sphere, having a diameter W, it is possible to correctly "frame" the target for all angular positions of its fore and aft axis relatively to the gun-target line so that the image of the target is in the correct position relatively to the reticle lines or segments, in the manner subsequently explained. From the figure

$$D_o \theta = W \text{ or } D_o = W/\theta \quad (10)$$

Equating the two values of D_o of Equations 6 and 10,

$$\frac{W}{\theta} = \left[\frac{SD_M}{\Sigma} \right]^{\frac{1}{2}} \text{ and } \theta = \frac{W}{(SD_M)^{\frac{1}{2}} \cdot \Sigma^{\frac{1}{2}}} \quad (11)$$

For a given target run S, D_M and W are constant. Hence

$$\frac{W}{(SD_M)^{\frac{1}{2}}}$$

is constant C, and for any two particular values of θ , $\theta_1 = C \Sigma_1^{\frac{1}{2}}$ and $\theta_2 = C \Sigma_2^{\frac{1}{2}}$

Hence

$$\frac{\theta_2}{\theta_1} = \left[\frac{\Sigma_2}{\Sigma_1} \right]^{\frac{1}{2}} \text{ and } \theta_2 = \theta_1 \left[\frac{\Sigma_2}{\Sigma_1} \right]^{\frac{1}{2}} \quad (12)$$

Thus, by varying the linear size of the pattern of reticle range lines within a field of view of the target, the correct lead angle between the gun and the line of sight to the target, may be introduced by "framing" the target between two reticle range lines and varying the linear dimensions of the pattern in proportion to $\Sigma^{\frac{1}{2}}$.

The manner in which this is accomplished will be made clear from the subsequent description of the operation.

Referring particularly to Fig. 3, 1 identifies a fixed base having a ring gear 2 formed upon its periphery. An upper gun carriage includes a disc 3 pivoted at its center on base 1 and having a flange or skirt 4 depending therefrom and serving to protect gear teeth 2. The carriage also includes spaced standards 5 and 6, fixed to disc 3 and formed at their upper ends with bearings, one of which is shown at 7. Aligned trunnions, not shown, extend from gun cradle 8 of gun 9 and are journaled in bearings 7 to define a gun elevation or trunnion axis 10.

A gunner's seat 11 is adjustably mounted upon rotatable disc 3 by means of a socket 12 and 90° arm 13 having a vertical portion fitting in socket 12 and a horizontal portion slidably received by the sleeve 14 affixed to seat 11. Set screws 15 threaded into the socket and sleeve, enable adjustment of seat 11 in a manner obvious from inspection of Fig. 3.

A vertical training shaft 16 has a hand wheel 17 affixed to its upper end in convenient location for operation by the left hand of the gunner in seat 11. This shaft is journaled in a bracket 18 fixed to disc 3 and carries a pinion 19 in mesh with the teeth on gear 2. Shaft 16 also carries a bevel pinion 20 in mesh with a second pinion 21. Pinion 21 is fixed to a stub shaft 22 journaled in

bracket 18. This shaft has its other end attached to one end of the core of a flexible shaft 23, whose other end extends to the computer and, as shown at Fig. 5, is there fixed to a shaft 34 journaled in a bracket 24 fixed to standard 5 by cap screws 25.

A stub shaft 26 is journaled in standard 5 and has an elevation hand wheel 27 and a pinion 28 attached to its outer and inner ends, respectively. A second shaft 29 is journaled in standard 5 adjacent and parallel to shaft 26, and has fixed thereto a pinion 30, in mesh with pinion 28, and a pinion 31 in mesh with an elevation gear sector 32 attached to cradle 8 concentric of trunnion axis 10. One end of the core of a flexible shaft 33 is attached to the outer projecting end of shaft 29. This shaft extends to the computer where its other end is attached to a shaft 35 journaled in bracket 24. The hand wheel 27 is in position convenient to the right hand of the gunner in seat 11. The connections are such that each hand wheel rotates in a plane parallel to and in the same sense as, the gun motion which it effects. Thus rotation of hand wheel 17 clockwise looking down therein, rotates the gun clockwise in train, while rotation of handwheel 27 clockwise, as seen in Fig. 3, elevates the gun. Thus the movements of the hand wheels correspond to the desired direction of movement of the gun, and facilitates smooth tracking, while reducing vertigo on the part of the gunner. The optical parts of the instrument will be subsequently described but it should be noted at this point that the eyepiece or ocular 35' is positioned conveniently to the eye of the gunner when in seat 11.

As best shown upon Fig. 5, a circular plate 36 is secured to bracket 24, concentric of trunnion axis 10. This plate has a central aperture in which a combined bracket and gear unit 37, is journaled for rotation about axis 10. This bracket comprises a vertical arm 38 and an integral hub 39 fitting the aperture in plate 36, and having a gear 40 attached to its end. Bracket 37 also has a horizontal arm 41 having a bearing 43 on its outer end. A shaft 44 is journaled on a normally vertical axis in this bearing and has a bevel gear 45 fixed thereto. At its top, shaft 44 carries a cup 46 on which a hollow sphere 47 rests and to which it is secured. The relations and dimensions are such that axis 10 passes through the center of sphere 47. A 90° angle 42 is fixed to the end of arm 41. A shaft 48 is journaled at its ends in this angle and vertical arm 38, and has a pinion 49 in mesh with pinion 45. A gear 50 is secured on shaft 48 and meshes with an idler gear 51 journaled on a stud shaft 52 on arm 38. Idler 51 meshes with a gear 53 which is fixed to a shaft 54 journaled in a bearing aperture in hub 39 on axis 10. A bevel gear 55 forms one side of a differential 55 and is attached to the outer end of shaft 54. The other side of this differential comprises a bevel pinion 56 and a gear 57 forming a composite element journaled on shaft 54. The center of differential 55 is formed of two or more planetary gears 58 journaled on a shaft 59 fixed to the end of shaft 54, in a manner clear from inspection of Fig. 5.

Shaft 35 is journaled at both ends in bracket 24 and has a pair of pinions 60 and 61 fixed thereto. An idler 62 is journaled on bracket 24 and is in mesh both with gear 57 and pinion 60. Pinion 61 is in mesh with gear 40.

The purpose of the foregoing construction is

to rotate bracket 37 equally and oppositely to the movement of the gun as it changes elevation about axis 10, to thereby maintain shaft 44 vertical for all positions of the gun in elevation, and to rotate shaft 44 equally and oppositely to movement of the gun in train to maintain all diameters of sphere 47 normal to the axis of shaft 44, fixed in direction.

Considering the case where handwheel 17 only is being turned to thereby train the gun. Shafts 23 and 34 are thus rotated proportionately to drive the planetary gears 58 of differential 55. Since side 56 of the differential is motionless at this time, by reason of being fixed through gears 57, 62 and 60 to shaft 23 which is not rotating, the drive continues through differential 55 by way of side 63 to shaft 54. Rotation of shaft 54 rotates sphere 47 about the axis of shaft 44 by way of gears 53, 51, 50, shaft 48, gears 49 and 45 and shaft 44. The driving ratios are so selected that, for any rotation of gun 8 clockwise in azimuth, for example, sphere 47 will be given an equal rotation counterclockwise. In this manner, sphere 47 is maintained fixed in azimuth for all positions of the gun in train.

Consider next the case where handwheel 27 only is rotated to change the elevation angle of the gun. The resulting rotation of shafts 33 and 35, drives pinion 61 and thereby gear 40, to rotate bracket 37 about axis 10. The connections and ratios are such that for any given change in the angle of gun elevation, bracket 37 is rotated equally and oppositely to maintain shaft 44 vertical. However, in case gear 53 were held stationary during change of elevation of the gun, idler 51 revolves or "walks around" gear 53 as bracket 37 rotates about axis 10 relatively to the gun. The resulting rotation of gear 51 and sphere 47 would cause a rotation in azimuth of sphere 47 which, unless compensated, would effect erroneous operation of the computer. To compensate this rotation, operation of shaft 35 also effects a drive by way of gears 60, 62 and 57 to side 56 of differential 55. Since planetary gears 58 are held motionless at this time, the drive continues through gears 58 and 63 to shaft 54 and thence, over the drive previously traced, to shaft 44 and sphere 47. The connections and gear ratios are such that gear 53 is rotated in the same direction and to the same extent, as vertical arm 38. As a result, pure elevation of the gun causes equal and opposite rotation of bracket 37 about axis 10, while gear 51 remains motionless relatively to the bracket and no rotation of shaft 44 and sphere 47 is effected thereby. For clarity of description, the two angular movements of the gun have been separately explained. However, it will be understood that the mechanical action is not altered in any way when the gun is simultaneously trained and elevated. The mechanism just described maintains the two component motions separate and distinct so that each is applied to the sphere about an axis parallel to the corresponding axis of gun movement. As a result sphere 47 is maintained rotationally fixed in space for all angular motion and for all angular positions of the gun.

The computer is housed in a casing 64 which, as shown by Fig. 3, is fixed to cradle 8 by a bracket 65. A removable cover 66 closes one side of the casing and is held in position by screws 67 engaging in tapped apertures in lugs 68, Fig. 4. The other side of casing 64 has an aperture 69, Fig. 5, smoothly fitting plate 36 and on which it rotates as the gun changes elevation.

The top of casing 64 carries a frame 70 which, as best shown at Fig. 6, includes two raceways for antifriction bearings 71 and 72 defining an axis 112 concurrent with and normal to, axial 10, and also passing through the center of sphere 47. A frame or housing 73 is journaled in and by these bearings. Frame 70 also carries a plurality of slip rings 75 and 76 mounted on dielectric inserts carried by bars 77 located at spaced intervals about the frame. At its top casing 64 has an aperture closed by the male portion 78 of a separable plug connector whose prongs 79 are electrically connected with the respective slip rings 75 and 76. Housing 73 has a dielectric plug 80 closing an aperture in its side wall. Brush connectors 82 and 83 are mounted in this plug, each resiliently engaging a respective one of slip rings 75 and 76.

A constant speed motor 84 is mounted by flange 85 within an aperture in the wall of housing 73 and has its leads 86 connected with respective connectors 82 and 83. Motor 84 drives a disc 88 of a variable speed drive 93 through reduction gearing including pinion 87 on the shaft of motor 84, gear 89, pinion 90 and gear 91, the latter being fixed to the shaft of disc 88. The reduction gearing, as well as the disc, are mounted upon a support 92 fixed to one end of housing 73.

Variable speed drive 93 is of conventional construction, and includes driven roller 94 journaled in one bearing 95 on the wall of housing 73 and a second bearing in frame 96 secured to the floor of housing 73. The speed-varying element includes a squared shaft 97 shaped to provide a cage for balls 98. This shaft also has a rack 99 formed thereon and, at its inner end, carries a cam 100, whose purpose and function will be subsequently described. The shaft 97 is guided for axial translation at the end adjacent cam 100, by rollers 101 journaled on the housing wall. Such translation moves balls 98 radially of disc 88 so that roller 94 is driven at a speed proportional to the radial position of the balls.

The end of housing 73 remote from support 92 is open, to receive the adjacent portion of sphere 47. An arcuate slide 102 is mounted within the open end of the housing concentric to the center of sphere 47 and is guided for angular movement about such center in a plane that passes through the center of the sphere for all rotational positions of housing 73 about the axis of bearings 71 and 72. This plane coincides with the plane of the sheet of Fig. 6 for the positions of the parts there shown. The movement of slide 102 is guided by any suitable construction such as that shown upon Fig. 15, where slide 102 is provided adjacent opposite ends with ribs 102a lying in a common diametral plane of sphere 47 and received in slots in the rim 73a of housing 73.

While if desired, means may be provided to positively prevent separation of slide 102 from housing 73, it is contemplated that the slide may be held in position by the action of a spring 103 and a roller or caster 105. Spring 103 is connected at one end to housing 73 and at its other end to an eye 104 on slide 102. The position of the spring is such that it exerts a force on slide 102, having one component holding the slide upon its seat, and a second component urging the slide into clockwise rotation as seen at Fig. 6. This latter component is sufficient to at all times hold a knob 106, secured to slide 102, in engagement with cam 100. In this manner, the axial position of shaft 97 and cam 100, determines the displace-

ment of slide 102 from its normal or central position.

Slide 102 has a slot 107 in its lower half within which caster 105 is journaled on a lever 108, pivoted to slide 102 at 109. A spring 110 acts between an abutment 111 on slide 102, and lever 108, to urge caster 105 into contact with sphere 47. The caster is so mounted in slide 102 that its point of contact with sphere 47 is at all times in the plane of movement of slide 102 about sphere 47 while its axis of rotation is perpendicular to that plane. Thus since housing 73 is free to turn about axis 112, roller 105 acts to place itself in parallelism with the plane of rotation of casing 64 about sphere 47. Since the casing moves as a unit with the gun as the latter moves in tracking a moving target, the caster thus acts to determine the apparent angle of approach or departure of the target, while the rate of rotation of the caster is dependent, with other factors, upon the speed of the target. For example, the position of the parts shown in Fig. 6, corresponds to a condition where the target is moving in a horizontal path directly toward the gun position. The effect of the relative rotation of casing 64 and sphere 47 can be readily visualized by imagining that the sphere is grasped and rotated in various planes about its center. Actually however, the sphere remains angularly fixed while the casing 64 and parts carried thereby, rotate about its center as the gun is moved to track a target.

Caster 105 is mounted in arm 108, by a shaft having one end attached to the core of a flexible shaft 113. The other end of this shaft 113 is connected with a worm 114 journaled in a portion of frame 96. This worm meshes with a gear unitary with bevel pinion 115 and forming one side of a differential generally identified by numeral 116. The center of differential 116 comprises a shaft 117 journaled in frame 96 and having planetary gears 118 mounted on one end and a pinion 119 on the other end. A second side of differential 116 comprises a composite gear 120 having one bevel pinion in mesh with planetary pinions 118, and a second bevel pinion in mesh with a pinion fixed to roller 94. The arrangement is such that side 120 of differential 116 is driven by motor 84 through variable speed device 93, in a direction opposite to that which caster 105 drives side 115. Hence, when the two sides are rotating at equal speeds, differential center 118 is motionless and shaft 97 remains fixed in position. This condition, for example, corresponds to a constant angular rate of tracking of the gun. However, when the rate changes the rate of rotation of side 115 differs from the rate of rotation of side 120. As a result center 118, shaft 117 and pinion 119, are rotated to effect axial translation of shaft 97 and shift balls 98 radially of disc 88. This acts to vary the speed of roller 94 and differential side 120 until the rates of the two sides are again equal. Thus, the axial position of shaft 97 is proportional to, and measure of, the angular rate of gun movement in tracking the target. Incidentally, it should be mentioned that housing 73 and all parts carried thereby, are balanced about axis 112 so that there is no pendulousness thereof and no tendency of the same to rotate, apart from the control imparted by caster 105. It will also be noted that axis 112 is maintained parallel to the bore axis of the gun.

From Figs. 4 and 6 it will be noted that housing 73 has a bevel gear 121 fixed to its end, and concentric of axis 112. This gear has a central aperture through which shaft 97 may pass with a

smooth fit. Gear 121 meshes with and drives a pinion 122 which is fixed to the upper end of a shaft 123. This shaft is journaled in a frame 124 attached to the adjacent wall of casing 64 and carries at its lower end, an elongated pinion 125 in mesh with a ring gear 126 fixed to the upper end of one section of an optical unit identified generally by the numeral 127.

The optical unit 127 includes three generally tubular axially, aligned sleeves. The upper sleeve 128 carries gear 126 and just below said gear is provided with a circumferential channel 131. An opaque, perforated reticle disc 132, Figs. 7 and 8, is provided with pivots 133 and 134, defining an axis coincidental with a diameter of the disc. These pivots are journaled in aligned bearing apertures in sleeve 128 whereby the disc is pivotally mounted in the sleeve. The pivot 134 extends beyond the outer surface of the sleeve where it carries a lever arm 135. The end of this lever is connected by a pivoted link 136, to intermediate sleeve 129.

Sleeves 128 and 129 are connected, by any suitable means, which permits relative axial translation only. Such means is shown, merely by way of example, with three guides 137, 138 and 139 extending upwardly from the periphery thereof, each slidably received in a corresponding channel in sleeve 128. Thus the two sleeves may have relative axial sliding but are compelled to rotate as unit, and because of link connection 135, 136 between the two sleeves, any relative axial motion effects a proportional pivotal movement of disc 132. The purpose and function of the perforations in the disc will be subsequently explained. Sleeve 129 has a circumferential channel 141.

Sleeves 128 and 129 are thus mounted for independent movement in the direction of their common axis. This movement of sleeve 128 is controlled by a rod 142 guided for axial translation by a bearing 144 in frame 124 and a socket 145 formed in base 146. A projection 147, attached to shaft 142 has an arcuate end forming a rider fitting within channel 131 and identical with the rider shown at 148 on rod 143, Fig. 8. A coil spring 149 is located in socket 145 and acts upwardly upon rod 142 to support its weight, as well as that of sleeve 128, and to urge the ball 150 on the upper end of the rod, into contact with a three-dimensional control cam 151 fixed to a shaft 152. The purpose of this cam will be subsequently explained.

Likewise, rod 143 is guided for axial translation by a bearing 153 provided in frame 124 and a socket 154 in base 146. This rod has a projection 148 forming a rider at its end which rider engages in channel 141. A coil spring 155 is located in socket 154 and acts to support the weight of rod 143 as well as sleeve 129, and to urge the antifriction ball 156 at the top of rod 143, upwardly into contact with three-dimensional cam 157 fixed upon shaft 152. It is contemplated that means may be provided for adjusting the thrusts exerted by springs 149 and 155 such as adjusting screws threaded through the base 146 and projecting into sockets 145 and 154.

The lower sleeve 130 is adapted to have a snug fit within aligned apertures in base 146 and casing 64 and to be axially adjustable therein. Means for positively so adjusting the sleeve may be provided if desired or found necessary. A circular bezel 158 is secured within sleeve 130 near its top and mounts a ground glass screen 159. A lens system, shown as a simple projecting lens

160, is secured over the lower end of sleeve 130 by a bezel ring 161 threaded thereon. A source of illumination such as a lamp 162 and reflector 163 are mounted on the wall of casing 64 above and centrally of sleeve 128. This source acts to cause an image of the perforations 140 to be projected upon screen 159, to produce an image thereof which is projected by lens 160 upon a partially silvered reflector 164 mounted by bracket 165 upon the wall of a sight casing 166. The reflector is positioned at 45° both to the common axis of sleeves 128, 129 and 130, as well as to the optical axis of eyepiece 35.

The construction just described operates to project an image of the slots in disc 132, upon ground glass screen 159 and thence to reflector 164 so that the gunner, looking through eyepiece 35, may see an image of the reticle superposed over the image of the target.

Shaft 152 is connected in alignment with a second shaft 168 by a swivel joint 167. Shaft 168 is mounted in a bearing 169 carried by the casing wall. Axial translation of shafts 168 and 152 as a unit, is effected by a lever 170 pivoted at 171, Fig. 4, upon frame 124 and connected by a pin and slot connection 172 to shaft 168. At its other end, lever 170 is connected by a pin and slot connection 173 to a shaft 174. Shaft 173 is mounted at one end in a bearing 174 on the wall of casing 64. The other end of this shaft is connected by a swivel joint 175 to the adjacent end of shaft 97. The two arms of the lever 170 are conveniently, but not necessarily, of equal length so that shaft 152 is axially translated in the same amount, but in the opposite direction, as shaft 97 under the action of differential 116, pinion 119 and rack 99. This translation, it will be remembered, is proportional to the rate of rotation of roller 105 over sphere 47 which, in turn, is proportional to the angular rate of movement of the gun in the slant plane determined by the gun position and target path. In short, shaft 152 and cams 151 and 157 carried thereby, are translated axially in proportion to Σ .

Shaft 152 has its end remote from joint 167 splined as at 176, Fig. 9, to the sleeve portion of an adjusting knob 177. This portion is journaled in an aperture in casing 64 convenient to the gunner, as shown upon Fig. 3. Axial movement of the knob is prevented by a circumferential channel 178 and a screw 179 having its end engaged therein. It is intended that knob 177, shaft 152 and cams 151 and 157 shall be rotated in accordance with the wing span of the target. To facilitate this adjustment, a scale 177a, graduated in wing span measured in feet, for example, may be attached to casing 64, for cooperation with a pointer 177b fixed to rotate with knob 177. In this manner, cams 151 and 157 are axially translated in proportion to the angular velocity of movement of the gun in the target slant plane as the gun is moved to track a target; and are rotated in proportion to the wing span of the target.

In Fig. 14, I have shown a modification of the reticle disc tilting mechanism wherein the projecting end of pivot 134 has a pinion 180 secured thereto, in mesh with a rack 181 pivoted at 183, to sleeve 129. The rack is held in engagement with the pinion by means of a leaf spring 184. In this manner relative motion of the two sleeves effects tilting of disc 132 in exact proportion to the amount of such motion.

Where a manually controlled source of power is used to control the gun, rapid slewing of the

gun, as when picking up a new target will generate excessive lead angles and lengthen the time necessary for the computer to reach a new steady state and for successful engagement of the new target. To obviate this, I use the circuit shown in Fig. 13 wherein are shown the leads 86, supplying constant speed motor 84 under normal operation, from ground at 184, lead 185, double-pole double-throw switch 186, lead 74, governor switch 187, leads 86, and current supply 188 to ground at 189.

Switch 186 is located in position for convenient operation by the gunner. Thus, where a single "handle-bar" control is used, the switch would be mounted directly thereon for ready operation. When so operated, connection between leads 185 and 74 is opened while connection is made between leads 81 and 190. The motor is now supplied over a circuit from ground at 191, auxiliary source of potential 192, lead 190, switch 186, leads 81 and 86, to ground at 189. The additional potential from source 192 causes motor 84 to rotate at increased speed and, since the rapid angular movement of the gun causes roller 105 to rotate at a greater rate, excessive axial displacement of shaft 97 is avoided.

Operation

The gunner has been trained to imagine the target surrounded and encompassed by a sphere having a diameter equal to its wing span W . This diameter is the controlling dimension used in "framing" the target between the reticle lines. Tests were conducted to obtain an initial estimate of the errors that might be expected by reason of the various possible attitudes of a target craft with respect to the line of sight. It was found that the average error to be expected is 2.4%. This error is small in comparison to those inherent in prior art gun-lead computing systems and may be further reduced by practice and experience in actual combat. Figs. 10 and 10a show typical appearances of the target when correctly "framed," the former being for a large range and the latter for a small range.

As soon as a target has been selected and identified, knob 177 is turned until pointer 177a indicates upon scale 177a the known wing span of the target. The gunner, while viewing the target through eyepiece 35' manipulates his controls to move the gun at a rate and in a direction necessary to continuously maintain the target "framed" between the image of the reticle lines. Since sphere 47 is maintained rotationally fixed, this movement of the gun causes roller 105 to move over the surface of the sphere in the slant plane in which the gun moves. Since housing 73 is pivoted in bearings 71 and 72, the caster action of roller 105, turns the housing until the plane of the roller lies in the aforesaid slant plane. This turning of housing 73, operates through gear 121, pinion 122, shaft 123, pinion 125 and ring gear 126, to rotate sleeves 128 and 129 as a unit about their common axis, to thereby rotate disc 132. The gear ratios and connections are such that the sleeves rotate synchronously with housing 73 and the axis of symmetry of the image of the reticle lines is parallel to the plane of rotation of the roller 105 and extends from the center of the field of view in the direction of displacement of the roller relatively to the adjacent intersection of axis 112 with sphere 47. For example, in the position of the parts shown upon Fig. 6, the aforesaid axis would ex-

tend vertically downward away from the center of the field of view.

Because of the action of the variable speed drive 93, the differential 116 and the connection with roller 105 and shaft 97, the latter is translated axially in proportion to the velocity of rotation of the roller. This translation is imparted through joint 175, Fig. 4, shaft 173, lever 170, and shafts 168 and 152, to impart a proportional translation to cams 151 and 157. These two cams are essentially of the same shape, the only difference being that cam 151, connected to sleeve 129, in addition to imparting to sleeve 129 the same axial movement that is imparted to sleeve 128 by cam 151, also imparts to sleeve 129 an additional axial movement that is a function of the angular velocity of castor roller 105 and the wing span of the target craft. The purpose of this feature will be subsequently explained.

Translation of cams 151 and 157, then, effects axial movement of rods 142 and 143, respectively, and sleeves 128 and 129. This movement shifts reticle disc 132 toward or from screen 159 and correspondingly varies the size of the image cast thereon and upon partial reflector 164. The cam 151 is shaped depending upon the constants of the instrument and the average velocity of the projectile for the most effective and usual range of the gun, to translate the reticle proportional to the square root of the angular velocity, e. g., proportional to Σ^2 in accordance with Equation 8, supra, so that any element thereof intersected by a radial plane through the axis of shaft 152, will translate sleeve 128 by an amount proportional to the square root of the angular speed of the castor or roller 105. The actual distances by which the sleeve is moved for any given translation of shaft 152, will, of course, depend upon the constants of the instrument, the ammunition used, and the average projectile velocity for the usual or most effective range of the gun. Each said element corresponds, under the conditions noted, to a craft of given wing span and is selected by rotation of knob 177 after the target craft has been identified as to type and size.

The lead angle thus computed is based upon the assumption that the average velocity of the projectile remains constant for all ranges. This of course is not strictly correct since the average velocity will decrease with increase of range. Assuming that the path of the target remains fixed in direction during the period between initial observation and impact of the projectile, and that a perpendicular is dropped to this path from the gun position and the intersection of the path and its perpendicular is the "mid-point" of the path. That portion of the path traversed by the target up to mid-point is termed the incoming leg while that portion of the path traversed by the target after passing mid-point is termed the outgoing leg.

On the incoming leg of the target path the angular speed of roller 105 will be a little less than the actual angular velocity of the target while on the outgoing leg, its angular speed will be a little greater than the actual value. At mid-point the two values are congruent. The slight errors thus introduced can be significantly reduced if the average velocity V_0 of the projectile to the present target position, T_0 , is substituted for the velocity, v , to the point of impact T_p used in Equation 4. Thus, on the incoming leg, the value of D_0/V_0 is greater than the correspond-

ing value of D_0/v and the product of D_0/V_0 with Σ as measured by the instrument, will be very close to the required lead angle. Likewise, on the outgoing leg of the target's path D_0/V_0 is less than the corresponding value of D_0/v and again the product of D_0/V_0 with Σ as measured by the instrument, will afford substantially correct values of Δ .

If in addition, the error caused by assuming $\sin \Delta$ to equal Δ , is reduced, accurate lead values are obtained.

The foregoing errors are substantially eliminated by the use of the additional cam 151 which, for increasing values of Σ , for example, translates sleeve 129 a distance greater than the corresponding translation of sleeve 128 effected by cam 151, by an additional distance. The cam is so proportioned that the corresponding pivotal movement of disc 132 is a function of Σ and W .

Superelevation corrections may be introduced by pivotally mounting reflector 164 in sight casing 166 about a normally horizontal axis lying in the plane of the reflector. Since superelevation is a function of the cosine of the angle of gun elevation, any well-known cosine corrector may be connected to be connected to be operated by elevation drive 28-32, inclusive. Such corrector may be directly connected to the pivotal mounting for the reflector. Fig. 16 shows a suitable corrector for this purpose where reflector 164 is indicated in dotted lines and is pivoted in casing 166 upon a shaft 163 having its axis in the plane of the reflector and to which a roller 194 is attached. A second roller 195 is journaled a short distance from 194. A frame 196 has arms resting upon rollers 194 and 195 whereby, in conjunction with auxiliary rollers 197 and 198 the frame is guide for translation only. Frame 196 has a slot therein, extending perpendicularly to the direction of translation of the frame. A flexible steel band 199 extends about rollers 194 and 195 and may be secured to 194, as indicated at 200. This band has its ends connected to frame 196 at points such as 201 and 202 whereby translation of the frame effects corresponding rotation of reflector 164. Preferably the arms of the frame rest upon the adjacent portions of the band. An eccentric 203 has a smooth fit in the slot of frame 196 and is journaled for rotation about an axis offset from its center. In Fig. 16 the direction of this offset is vertically downward so that, the position of the parts shown corresponds to a 90° angle of gun elevation with reflector 164 at 45° to the axis of the gun bore. A tightener may be provided for band 199 in the form of a roller 204 guided for movement transversely of and in contact with the band. Turning of screw 205 thus acts to tighten the band without causing any rotation of roller 194. Eccentric 203 is connected by any suitable drive means, not shown, for rotation by elevation shaft 33 or pinion 61. The driving ratio is such that the eccentric is rotated equally and oppositely to movement of the gun in elevation and hence remains angularly fixed relatively to the vertical. Thus as the sight moves with the gun in changing elevation, reflector 164 is pivoted in accordance with the cosine of the angle of gun elevation.

Corrections for changes in muzzle velocity of the projectile and in air density, may be effected by modifying the target size adjustment of knob 177. For example, scale 177a may itself be rotatable in accordance with a combined factor of muzzle velocity and air density. Knob 177 may then be set relatively to the scale, in accordance

with the known size of the target, as previously explained.

It will thus be noted that I have invented a lead-computing gun sight that is relatively simple, entirely automatic in operation after setting for target size, and simple and easy to operate. The proper lead angle is continuously introduced so long as the gun is properly tracking the target so that firing is limited only by the loading mechanism of the gun itself. Except for the motor 84, all parts are mechanical in operation and there are no delicate and easily deranged telemetric drives from a remote computer. The sight can be made relatively small and compact and once attached and adjusted, remains constant in operation throughout the life of the gun.

In the specification, the term "elevational movement" includes movement of the gun to decrease its angle of elevation, as well as movement to increase its angle of elevation.

For simplicity of explanation and illustration, the gun has been shown as being directly manually actuated. This disclosure is illustrative only. The actual control used will depend upon the type and size of gun. It is clear that, for guns of relatively large caliber, hydraulic or electric power will be used under the control of the gunner. Such control may be effected by any of the well-known "joy-stick" or "handle-bar" controls where a single control element is used mounted for movement in two angularly-related planes. This element is connected to the power means such that movements in the two planes effects motion of the gun in corresponding planes. Suitable controls of this type are illustrated in the patents to Rolcik, 2,107,803, February 8, 1938, for "Adjusting Mechanism for Firearms" and Adams et al., 2,350,662, June 6, 1944, for "Hydraulic System and Control." Any other of the control systems of this type may be used so long as the motions of the gun in azimuth and elevation are transmitted to shafts 34 and 35 respectively.

The term "axis of the reticle lines" is the line corresponding to the radius of disc 132 about which the reticle range lines defined by slots 140, are symmetrical. This axis, as shown upon Fig. 8, is perpendicular to the pivot axes determined by pivots 133 and 134.

The term "framed" as used in the claims means a position of the gun and sight in which the imaginary sphere surrounding the target, and having a diameter equal to the wing span of the target is tangent to both of the reticle range lines.

The caster angle of roller 105 is the angle defined by axis 112 and the radius of sphere 47 through the point of contact of roller 105 therewith.

While I have disclosed the preferred form of the invention as now known to me, it will be clear to those skilled in the art, to which this specification is addressed, that numerous substitutions of equivalents, and modifications are possible without altering in any way the basic principles upon which the instrument operates. It is therefore intended that the present disclosure shall be taken in an illustrative sense only. It is my desire and intention to reserve all such changes as fall within the scope of the subjoined claims.

Having now fully disclosed my invention what I claim and desire to secure by Letters Patent is:

1. In a computing gun sight adapted to be

carried by a gun for angular movement therewith in elevation and train, a bracket adapted to be journaled on said gun for pivotal movement relatively to said gun about a first axis coincident with the axis of gun elevation, a sphere pivoted on said bracket for rotation about a second axis coincident with a diameter of said sphere and normal to and concurrent with said first axis, a drive shaft journaled in said bracket coincident with said first axis, means carried by said bracket and connected with said shaft and sphere to rotate said sphere about said second axis in response to turning of said shaft, a differential having one side connected to rotate said shaft, an azimuth shaft connected to drive a second side of said differential, an elevation shaft, and means connecting said elevation shaft to simultaneously rotate said bracket about said first axis and turn the third side of said differential.

2. In a lead-computing gun sight, a sphere adapted to be mounted upon a gun for universal rotation with respect thereto, means connecting said sphere with the gun to maintain the sphere angularly fixed for all positions of train and elevation of said gun, a housing, means mounting said housing for angular movement as a unit with said gun and for rotation about a first axis coincident with a diameter of said sphere parallel to the bore axis of said gun, and roller means carried by said housing and in driven engagement with and rotated by said sphere whereby said housing is rotated about said first axis in accordance with the plane of movement of said gun in tracking a target.

3. The combination with a gun elevatable upon a trainable support, a sphere mounted upon said support for pivotal movement about a first axis parallel to the axis of elevation of said gun, and a second axis normal to said first axis, means responsive to change of elevation of said gun to rotate said sphere about said first axis equally and oppositely to said change to thereby maintain said second axis normally vertical, means responsive to training movement of said gun to rotate said sphere about said second axis equally and oppositely to said movement, a housing, means mounting said housing for elevation and training with said gun and for rotation about a third axis parallel to the bore axis of the gun and forming a diameter of said sphere, a slide carried by said housing arcuately movable about the center of said sphere in a plane containing said third axis, a roller engaging said sphere and journaled on said slide for rotation in said plane, said roller acting to turn said housing about said third axis in accordance with the plane of movement of said gun and third axis in tracking a target.

4. The combination specified in claim 3, a variable speed drive carried by said housing, a motor connected to operate said drive, a differential having one side connected with the output of said drive and a second side connected to be driven by said roller, and means operating the speed-varying element of said drive in response to operation of the third side of said differential.

5. The combination specified in claim 3, a constant speed motor carried by said housing, a variable speed drive having an input operated by said motor and a speed-varying element translatable along said third axis, a differential, a driving connection between a first side of said differential and the output of said variable speed drive, means operating a second side of said dif-

5

ferential by and in response to rotation of said roller, a driving connection between the third side of said differential and said element, and means operable to move said slide by and in response to translation of said element.

6. For use in a lead-computing gun sight, a housing adapted to move with the gun in elevation and train and rotatable about an axis parallel to the bore axis of a gun, a spherical surface adjacent said housing adapted to be angularly fixed, said axis being coincident with a radius of said surface, a slide mounted on said housing for rotation about the center of said surface in a plane containing said axis, a roller journaled on said slide for rotation in said plane, means yieldingly holding said roller in contact with said surface, and means operable to angularly displace the point of contact of said roller and sphere from said axis proportional to the speed of rotation of said roller over said surface.

7. In a lead-computing gun sight, a sphere, a roller, means mounting said roller in contact with said sphere for rotation thereby and for revolution about a diameter of said sphere, and means responsive to the rate of relative rotation of said roller and sphere about the center of the sphere to vary the angle between said diameter and the radius of said sphere to the point of contact of said roller therewith.

8. In a lead-computer for guns, a sphere, a housing rotatable adjacent said sphere on a first axis coincident with a diameter of said sphere, a roller, means carried by said housing mounting said roller in driven contact with said sphere and for revolution about the center of said sphere in a plane containing said first axis and for rotation about a second axis normal to said plane, and means responsive to the rate of rotation of said roller about said second axis in response to rotation of said sphere about its center to revolve said roller relatively to said sphere in said plane and thereby to vary the angular relation between said first axis and the radius of said sphere to the point of contact of said roller.

9. In a lead-computing gun sighting device, a sphere, a housing rotatable about a first axis coincident with a diameter of said sphere, a variable speed power drive carried by said housing, a shaft axially translatable in said housing along said first axis, means varying the driving ratio of said variable speed drive by and in response to translation of said shaft, first means connected to rotate with said housing about said first axis and slidable in an arcuate path about the center of said sphere in a plane containing said first axis, a roller carried by said means in driven engagement with said sphere and rotatable about a second axis normal to said plane, a differential carried by said housing, and having first and second sides driven respectively by said roller and the output of said variable speed drive, means connecting a third side of said differential to axially translate said shaft, and means to slide said first means by and in response to translation of said shaft to vary the displacement of said roller from said first axis in accordance with a function of the speed of rotation of said roller about said second axis.

10. The device recited in claim 9, said last named means including a cam secured to said shaft and engaging a portion of said first means to displace the same, said cam being formed to displace said roller in accordance with the square

root of the rate of rotation of said roller about said second axis.

11. In a computing gun sight, a casing adapted to be mounted for movement with a gun in elevation and train, means carried by said casing defining a line of sight parallel to the bore of said gun and including a field of view surrounding said line, a disc bearing a pair of reticle range lines thereon symmetrical about an axis, means projecting an image of said lines into said field of view, means responsive to the movement of said gun in tracking a target to maintain the axis of said reticle lines parallel to the apparent path of movement of the target, and means responsive to the rate of angular movement of said gun and sight to bodily move said disc relatively to said casing to vary the apparent size of the image of said reticle lines in accordance with a function of said rate.

12. In a computing-sight for a gun, a frame adapted to move synchronously with said gun in train and elevation in tracking a moving target, first means responsive to movement of said gun in tracking a target to determine the direction of the path of said movement, second means responsive to said movement to determine the angular rate thereof, a sighting device determining a line of sight parallel to the bore of said gun and defining a field of view surrounding said line, means defining a pair of parabolic reticle range lines symmetrical about an axis, means projecting an image of said lines into said field of view with said axis concurrent with said line of sight, means responsive to said first means to rotate said axis about said line to maintain said axis parallel to the plane of movement of the gun as it is moved to cause said line of sight to track the target, and means responsive to said second means to vary the separation of the images of said lines as seen in said field of view in accordance with the rate of angular movement of said gun.

13. A computing gun sight for a gun elevatable upon a trainable platform comprising a casing adapted to be connected with said gun for movement as a unit therewith, first means carried by said casing to determine a line of sight substantially parallel with said gun and including a field of view about said line, second means in said casing defining a pair of spaced reticle range lines symmetrical about an axis, means projecting an image of said lines into said field of view with said axis concurrent with said line, means responsive to angular movement of said gun in tracking a target maintaining said axis parallel with the apparent path of said target, and means responsive to the rate of said angular movement to move said second means to vary the linear dimensions of the image of said lines.

14. In a lead-computing gun sight, first and second elements connected for rotation as a unit about a first axis and mounted for independent translation along said axis, a reticle disc pivoted on said first element on a second axis normal to said first axis and lying in the plane of said disc, means pivoting said disc about said second axis by and in response to relative axial translation of said elements, sighting means, means to project an image of the reticle on said disc into the field of view of said sighting means, and cam means operable to simultaneously translate said units at different rates to thereby vary the size of said image and alter the linear scale thereof in two mutually normal directions.

15. In a lead-computing gun sight, a sight, first and second sleeves rotatable about a common

first axis and independently translatable along said axis, a disc having a reticle pattern thereon and pivoted in said second sleeve on a second axis normal to said first axis and lying in the plane of said disc, means to project an image of said reticle pattern into the field of view of said sight, means rotating said disc about said second axis by and in response to relative axial translation of said sleeves, a rotatable shaft, first and second cam means fixed on said shaft, means translating each sleeve at different rates by and in response to rotation with said shaft of a respective cam means, whereby to simultaneously translate and pivot said disc to vary in two mutually normal directions, the linear scale of said reticle pattern.

16. The combination specified in claim 15, said shaft being rotatable in accordance with the known wing span of a target aircraft, said reticle pattern comprising range lines symmetrical about a third axis normal to and intersecting said second axis.

17. For use in a lead-computing gun sight, a sighting means adapted to be maintained parallel to the bore axis of a gun and to include a field of view about said axis, first and second sleeves connected for conjoint rotation about a common axis, a disc pivoted in one said sleeve on an axis in the plane of said disc and normal to said common axis, there being means on said disc defining reticle range lines symmetrical about an axis normal to the pivot axis of said disc, means projecting an image of said lines into the field of view of said sighting means, means pivoting said disc in response to relative axial translation of said sleeves, means rotating said sleeves as a unit in accordance with the slant plane of movement of the gun in tracking a target, and means differentially translating said sleeves by and in response to a combined function of the angular speed of said gun movement and a known dimension of the target.

18. A lead-computing gun-sight comprising a sight, means defining a pair of parabolic reticle range lines symmetrical about an axis, means to project an image of said lines into the field of view of said sight, means responsive to movement of said sight as said sight is moved to maintain said target framed between said lines to rotate said image to maintain the axis of the image of said lines parallel with the apparent path of the target, and radial of the optical axis of said sight, and means responsive to the resulting rate of angular movement of said sight to vary the linear separation of the image of said lines.

19. A lead-computing gun sight comprising sighting means, means adapted to project the image of a pair of spaced reticle range lines into the field of view of said sighting means, said lines being symmetrical about an axis radial of said field of view, means responsive to angular movement of said sighting means in maintaining a moving target framed between said lines, to rotate said axis into parallelism with the apparent path of said target, and means to vary the scale of said lines as viewed in said sighting means, in accordance with the wing span of said target and the square root of the rate of the angular movement of said sighting means.

20. In a lead-computing gun sight, sighting means, means operable to project the image of two reticle range lines into the field of view of said sighting means, said image lines being symmetrical about an axis extending radially of the center of said field of view, means responsive to angular movement of said sighting means in

maintaining a moving aircraft framed between said lines to rotate said axis into the plane of said movement, and means adjustable in accordance with the wing span of said aircraft and automatically responsive to the rate of said angular movement, to vary the scale of said image lines in said field of view.

21. In a lead-computing gun sight adapted to be mounted for movement as a unit in train and elevation with a gun, a sight including a partially silvered reflector interposed at an angle across the field of view of said sight and pivoted on an axis in the plane of said reflector transversely of said sight, means projecting an image of a pair of reticle range lines upon said reflector, said image lines being symmetrical about an axis radial of said field of view, and means responsive to the angle of gun elevation to pivot said reflector in accordance with the cosine of said angle to correct said sight from superelevation.

22. In a lead-computing gun sight, a casing adapted to be mounted for movement as a unit with a gun in train and elevation, a spherical surface, means rotating said surface about its center in response to angular movement of said gun, a housing in said casing rotatable on a first axis parallel to the bore axis of said gun and forming a radius of said surface, a slide guided for movement on said housing in an arcuate path about the center of said surface and in a plane containing said first axis, a caster engaging said surface and rotatable on said slide on an axis normal to said plane, a shaft in said housing extending along said first axis, means responsive to rotation of said caster over said surface to axially translate said shaft proportional to the rate of caster rotation, a sighting means movable with said casing in parallelism with said first axis, an optical unit in said casing to project the image of spaced, symmetrical reticle range lines into the field of view of said sighting means, said unit comprising a pair of elements relatively translatable along a common second axis and rotatable as a unit about said second axis, a reticle disc pivoted on one said element and connected with the other said element for pivoting in response to relative translation of said elements, means rotating said elements about said second axis in response to rotation of said housing by said caster about said first axis, and means differentially translating said elements to thereby pivot said disc in response to translation of said shaft.

23. A computing gun sight as specified in claim 22, said last-named means comprising a second shaft, first and second three-dimensional cams thereon, means operable by said cams in one dimension to differentially translate said elements, respectively, and manually operable means for adjusting said cams in a second dimension in accordance with a known dimension of a target.

24. That method of aiming a gun at a moving target comprising, establishing a line of sight parallel to said gun and including a surrounding field of view, providing a pair of reticle range lines in said field of view, symmetrical about an axis radial of said line of sight, rotating said axis about said line of sight to maintain the same parallel to the apparent path of said target as said gun and sight are angularly moved to maintain said target framed between said reticle lines, and varying the spacing of said lines in accordance with a function of the rate of said angular movement.

25. That method of aiming a gun at a moving

target, comprising, establishing a line of sight parallel to said gun and surrounded by a field of view, providing a pair of spaced reticle range lines in said field, symmetrical about an axis extending radially of said line of sight, angularly moving said gun and line of sight as a unit to maintain the target framed between said reticle lines, simultaneously rotating said axis to maintain the same parallel to the apparent path of said target, and varying the spacing of said reticle range lines in accordance with the square root of the rate of angular movement of said gun, while maintaining said target framed therebetween.

26. In a lead-computing gun sight, a casing carried by a gun to move therewith in train and elevation, a sphere in said casing, means maintaining said sphere fixed against rotation for all angular positions of said gun, a frame journaled in said casing for rotation on a first axis parallel to said gun and passing through the center of said sphere, a caster engaging said sphere and mounted on said frame for angular movement about the center of said sphere in a plane containing said first axis and for rotation in said plane, a motor carried by said frame, a variable speed drive driven by said motor, a differential carried by said frame and having one side driven by the output of said variable speed drive, a second side driven by rotation of said caster and a third side connected to vary the speed of said variable speed drive, and means driven by said third side to alter the caster angle of said caster about said sphere.

27. In a lead computer for a gun, a fixed sphere, a support, means mounting said support for angular movement about the center of said sphere in synchronism with the gun and for rotation about a first axis coincident with a diameter of said sphere, a roller, means mounting said roller on said support for driven contact with said sphere for revolution about said sphere in a plane containing said first axis, and for rotation about a second axis normal to said plane, and means responsive to rotation of said roller for revolving the same about said sphere to vary the angular relation between said first axis and the radius of said sphere to the point of contact of said roller therewith.

EDWIN H. LUDEMAN.
